ORIN BENNETT, OF PLACERVILLE, CALIFORNIA.

TYPE-OPERATING MECHANISM FOR TYPE-WRITING MACHINES.

1,168,704.

Specification of Letters Patent.

Patented Jan. 18, 1916.

Application filed January 18, 1915. Serial No. 2,840

To all whom it may concern:

Be it known that I, ORIN BENNETT, a citizen of the United States, residing at Placerville, in the county of Eldorado, State 5 of California, have invented certain new and useful Improvements in Type-Operating Mechanism for Type-Writing Machines; and I do declare the following to be a clear, full, and exact description of the same, such: 10 as will enable others skilled in the art to which it appertains to make and use the same, reference being had to the accompanying drawings, and to the characters of reference marked thereon, which form a part of 15 this application.

This invention relates to improvements in typewriting machines and particularly to the type operating mechanism therefor, the object of the invention being to produce 20 an electric operating means for driving the type against the platen, such electrical means being controlled by the movement of the keys of the typewriter in such a manner that the keys, by being lightly touched, may 25 be so thrown into action as to cause such electrical apparatus to operate the type bars to drive the type against the platen in an accurate and uniform manner, thus enabling 30 the best work to be done upon the type-writing machine with very little effort on the part of the operator.

The device is also designed for use not only on regular small type machines, but can be adapted for use on large type machines 35 for writing newspapers, bulletins, placards, or other similar large type matter. The same principle of invention is disclosed in my pending application for patent, filed August 21st, 1914, Ser. No. 857,841, and the 40 present application merely relates to improved details of construction and operation in connection with the same.

A further object of the invention is to produce a simple and inexpensive device and 45 yet one which will be exceedingly effective for the purposes for which it is designed.

These objects, I accomplish by means of such structure and relative arrangement of the parts as will fully appear by a perusal 50 of the following specification and claims.

On the drawings, similar characters of reference indicate corresponding parts in the several views.

Figure 1 is a cross sectional view of a 55 machine showing my improved structure thereon. Fig. 2 is a top plan view of the

same showing but one of the operating keys and its connection with the balance of the mechanism. I have not shown the balance of the keys as it would only confuse the 60 illustration, but it will be understood that each key is applied and operated the same as will be described for this one key. Fig. 3 is a detached detailed view of the operating key. Fig. 4 is a fragmentary side elevation 65 of a type carriage centering mechanism. Fig. 5 is a sectional view of the same taken on a line X—X of Fig. 4. Fig. 6 is a top plan view of the type operating hammer. Fig. 7 is a side elevation of the upper 70 portion of the type operating hammer.

Referring now more particularly to the characters of reference on the drawings, the numeral 1 designates the frame of the machine which may be of any suitable structure 75 and mounted on which is the usual type carriage 2 carrying the platen 3. This carriage is operated in any suitable manner, hence I have merely outlined the same in the drawing and make no particular claim to the 80 means of operating the same, nor of the ribbon mechanism or other details of the machine, my invention being confined solely to the type operating mechanism.

In carrying out the construction of my 85 improved invention, the same embodies certain subdivisions of construction and operation, namely: the type rack; the type rack operating and controlling mechanism; the key controlling mechanism for the type 90 rack and type bar mechanism; the electrically operated hammer mechanism for operating the type bars; and lastly, the keys and connections for throwing the electrically controlled structure into operation. 95

Describing first the type rack, this is of a rotary type and consists of a vertical shaft 4 suitably journaled in a supporting frame 5 and provided with two spaced arms 6 and 7. On the arm 6 is an annular ring 8 and on the 100 arm 7 is an annular ring 9. The type bars 10 are each secured to resilient strips which are secured in the ring 8 and normally rest against the ring 7. These type bars 10 carry the type 11 which project adjacent the 105 platen 3.

Describing next the type rack operating mechanism, the numeral 12 designates a pinion disposed on the shaft 4 and meshing with this pinion 12 is a geared quadrant 13 secured to the shaft 14 suitably journaled in a frame 15 at its upper end and in a frame

16 at its lower end. With the movement of the shaft 14, the rack 13 will likewise be moved, which in turn will move the pinion 12 and incidentally the shaft 4 and turn the 5 type rack to turn one or the other of the type bars 10 and its corresponding type 11 adjacent the platen 3. This operation is carried on through the medium of the key 10 controlling mechanism for the type rack 11 operating mechanism. This last mentioned structure comprises primarily the key 17 mounted on the key lever which comprises two members 18 and 19 pivotally mounted together, as at 20, the member 19 being turn- 15 ably mounted on a shaft 21 secured in the frame 1. The lever 18 has a portion 18^a projecting beyond the pivotal point 20 and connected with a spring 22 which normally is of sufficient tension to prevent the portion 20 18 from moving on its pivotal point 20 when the key 17 is first depressed, but causing the members 18 and 19 to move as a unit on the fulcrum point 21 until certain conditions 25 arise, as will appear. Each member 19 is provided with an inclined cam 23 terminating in a lug 24 to form an intermediate slot 25, projecting into which slot, through the lug 24, is a set screw 26. With the downward movement of the members 18 and 19 as 30 a unit, the cam 23 comes into contact with a finger member 27 secured on a shaft 28. The engagement of the finger member 27 with the inclined cam 23 moves such member 27 along the surface of said cam and turns the shaft 28, which action likewise turns an arm 29 secured on said shaft 28. The movement of this arm 29 operates a rod 30 connected by a ball and socket joint 31 with an arm 32 secured to the shaft 14 so that 35 through the movement of the key 17, the said shaft 14 will be moved to turn the type rack to bring that type which corresponds to the operated key adjacent the platen 3. The movement of the type rack must therefore be controlled so that for different keys a 40 different amount of movement will be had to bring a different type adjacent such platen 3. This adjustment of movement is occasioned by adjusting the degree of movement of the 45 finger member 27 along the inclined cam 23 and is fixed by means of a double structure consisting first of the adjustment set screw 26 which can be set at different points in the slot 25 and secondly, by having the finger member 27 consisting of two parts, one 50 slightly resilient and the other, as at 27^a, rigid. The portion 27 would then be fixed at the lower end of the portion 27^a by means of a screw 27^b and then through the upper 55 end of the member 27^a I would provide a set screw 27^c bearing against the member 27 to fix it at different relative positions to increase or decrease its amount of travel over the inclined cam 23. By means of these 60 adjustments, each key could have a different 65

degree of movement in connection with its corresponding finger member 27 to impart to the shaft 28 a different degree of movement, which, transmitted through the mechanism described, would operate the type 70 rack in the manner set forth. The type bars 10 are secured on the type rack in a circular manner as set forth and in such a way as to leave a blank space 33 normally adjacent the platen 3. This normal position is maintained by means of two spaced spiral springs 75 34 and 35 secured on the shaft 14 and each provided with an arm 36 and 37, respectively, projecting obliquely in spaced relation and normally engaging a stop member 38, in which position the type rack will be so locked that the blank space 33 will be adjacent the platen 3. When the type rack is operated in one direction or the other, the corresponding arm 36 or 37 will move away 80 from the stop member 38. Then when the key 17 is released and pulled back to normal position by the spring 22 in a manner as will be hereinafter described, the spring 34 or 35 will throw the said arm back until it strikes 85 the stop member 38 to reset the type rack in its normal position. In this normal position, it is locked by means of a spring pressed dog locked in the stop member 38 and engaging a notch 40 in a curved plate 41 secured on an arm 42, which arm is connected with the shaft 14. In view of this locked position, it will be noted that it becomes necessary to release the dog 39 from the notch 40 before the shaft 14 can move at all, and this is accomplished as follows, namely. There is a slight space 43 between the normal positions 90 of the cam 23 and the finger member 27 and while the key lever 18—19 is moving through this slight space, it carries a finger member 44 against a cross bar 45 pivoted on the shaft 21, as at 46, and lifts said bar 45 upwardly. This movement likewise lifts a finger member 47 secured on the bar 45, which finger member engages an inclined surface 48 on a pivoted arm 49 to which is connected the spring pressed dog 39. This engagement 95 moves the arm 49 backward against the spring 50 and disengages the dog 39 from the notch 40 leaving the shaft 14 free to 100 turn.

When the type rack has turned and brought the appropriate key adjacent the platen 3, it becomes essential that it be held rigidly in that position in order to obtain the best possible operation of the type bar and this rigidity is occasioned as follows: By this time the finger member 27 has come to a stop against the adjustment screw 26 so that no further movement of the part 19 105 can be had on the fulcrum point 21 so the tension of the spring 22 is overcome and the member 18—18^a moves on its fulcrum point 20. This brings the end of the member 18^a into contact with a cross bar 51 sus- 110

pended on curved arms 52 suitably fulcrumed, as at 53^a. When the member 18^a engages said cross bar 51, it moves the same and brings it into contact with a cam 52^a secured on a curved arm 53 connected with a spring controlled shaft 54. The shaft 54 is provided with a beveled gear 55 which in turn meshes with a beveled quadrant 56 on a vertical shaft 57. This shaft 57 is provided with an arm 58 having bent at right angles thereto a finger member 59, which, with the turning movement of the shaft 57, will be brought into engagement with one of a series of notches 60 on the ring 8. Thus, through the medium of the structure just described, when the type rack has moved to a certain position, the finger member 59 will immediately drop into engagement with one of the notches 60 to hold the type rack rigid while the type is driven into contact with the platen 3. When the mechanism is released, a spring 61 returns the shaft 54 and its connected parts to normal active position. The type rack having been turned to the position described and locked thereon in the manner specified, the next mechanism to be called into action is the electrically controlled hammer mechanism for driving the type against the platen 3. This consists of an enlarged hammer head 62 having a reduced portion 63 movable between guides 64 on a suitable frame 65 disposed within the contour of the type rack. Said reduced portion 63 then bends downwardly and is fulcrumed, as at 66, to the said frame 65. On the lower end of this hammer is provided a small fiber or rubber bumper 67. The numeral 68 designates the operating lever for striking the hammer 62-63 to drive it against one of the type bars 10 to bring the corresponding type against the platen 3 and is provided at its upper end with a bumper head 69 for the purpose of engagement with the bumper 67. This lever 68 is pivotally mounted on a shaft 70 and at its upper end is provided with a projecting arm 71 pivotally connected, as at 72, with a metal rod 73 which forms a core for a solenoid 74. This rod projects normally part way into the solenoid to a point, as at 75, where it is then connected with a fiber continuation 76 projecting beyond the end of the solenoid 74 where it is threaded, as at 77, to receive an adjustment nut 78 for adjusting the position of the parts to efficient operation. When the solenoid 74 is charged with electricity, it attracts the core 73 which pulls on the arm 71 and operates the lever 68 to cause the bumper head 69 to engage the bumper 67 on the type hammer 62-63. This drives the hammer against one of the type bars 10 to carry the type 11 against the platen 3. The said solenoid 74 is electrified by means of the operation of the keys and connections for throwing the electrically

controlled structure into operation. This embodies primarily the key 17 and the lever 18-18^a. When this lever moves on its fulcrum point 20 and lifts the rod 51 upward, such rod 51 comes into engagement with a cam 79 on a lever 80 fulcrumed at 81, said lever at its other end being provided with a projecting finger member 82 engageable with a lever 83 fulcrumed, as at 84, upon a switch plate 85. On the switch plate 85 is turnably mounted an annular cam 86 having a contact point 87 connected therewith.

The numeral 88 designates another contact point adjacent the point 87 but secured stationary to the member 85. A wire 89 leads from a source of electrical energy 90 through a make and break switch board 91 from which switch board a wire 92 connects with the point 87. Another wire 93 leads from the contact point 88 to the solenoid 74 while still another wire 94 leads from the solenoid 74 back to the switch 91 from whence a wire 95 leads again to the source of electrical energy 90. The points 87 and 88 are normally held out of engagement with each other by means of a dog 96 on the lever 83, which dog engages a notch 97 on the cam 86 to hold such cam in a position in which the point 87 will be spaced from the point 88. When however, the bar 51 is brought into engagement with the cam 79 in the manner specified, this will move the lever 80 on its pivotal point 81 and cause the finger member 82 to engage the lever 83 and disengage the dog 96 from the catch 97. A spring 98 then acts to rotate the cam 86 and throws the points 87 and 88 together. This completes the circuit, electrifying the solenoid as follows, from the source of electrical energy 90 through the wire 89, switch 91, wire 92, points 87 and 88, wire 93, solenoid 74, wire 94, switch 91, wire 95 and finally back to the source of electrical energy 90. The electrifying of the solenoid 74 causes the same to act on its core 73 to pull the bumper head 69 against the bumper head 67 with the result that the type bar 10 and its corresponding type 11 will be driven against the platen 3. When the operator releases the key 17, the spring 22 will pull the lever 18-18^a back into normal position with the result that this will release the bar 51 from engagement with the cams 52^a and 79. With the release of the cam 52^a, the spring 61 will act to turn the shaft 54 which, through its connections, will release the finger member 59 from engagement with the notch 60 and the spring 34 or 35 will then rotate the shaft 14 to return the type rack back to normal position in which it will be locked by the engagement of the dog 39 with the notch 40 in the manner described. With the release of the cam 79, a spring 99 acts to return the lever 83 to normal position and the cam 86 has already been returned to allow of the en-

gagement with the notch 97 therein by the dog 96 by reason of the following operation, namely: When the lever 68 is moved forward to bring the bumper head 69 and 67 into engagement, a set screw 100, on a finger member 101 at the lower end of the lever 68, engages a lever 102 fulcrumed, as at 103, connected with which is a link 104. This link 104 is connected with the cam 86 so that with the movement of the lever 102, the said cam 86 will be moved to return it to normal position to allow of the engagement of the parts 96 and 97, as aforesaid. A spring 105 maintains the normal position of the lever 102 and also aids the spring 98 in its action of turning the cam 86 when the same is released and ready for action. As the lever 83 moves to release the dog 96 from the catch 97, it moves a spring pressed pin 106 into the path of another notch 107 on the cam 86 to limit the movement of such cam so that an exact and fixed contact between the points 87 and 88 will be made with each operation and by no possible chance could the cam 86 be forced so far around as to break such contact.

In order to get the best operation of the solenoid 74 with the least amount of friction and binding, I have pivotally mounted such solenoid in trunnions 108 with suitable adjustments so that the same will move slightly each time on such pivotal connections in order to conform to and compensate for the arc described by the lever 68 in its movement.

The normal inactive position of the type hammer 62—63 is maintained by a spring 109 interposed between such hammer and an adjustment screw 110 to regulate the tension thereof.

From the foregoing description it will readily be seen that I have produced such a device as substantially fulfills the objects of the invention as set forth herein.

While this specification sets forth in detail the present and preferred construction of the device, still in practice, such deviations from such detail may be resorted to as do not form a departure from the spirit of the invention.

Having thus described my invention, what I claim as new and useful, is:—

1. A device of the character described comprising the combination with a type rack and type bars, of a means for striking such type bars, such means comprising a pivoted hammer capable of engaging said type bars, a lever fulcrumed independently of said

hammer and adapted to engage the same, a solenoid pivotally mounted, the core of said solenoid being flexibly connected with said lever and means for electrifying said solenoid to cause it to operate to pull said lever into engagement with said hammer, as described. 65

2. A device of the character described comprising the combination with a type rack and type bars, of a means for striking such type bars, such means comprising a pivoted hammer capable of engaging said type bars, a lever fulcrumed independently of said hammer and adapted to engage the same, a solenoid pivotally mounted, the core of said solenoid being flexibly connected with said lever and means for electrifying said solenoid to cause it to operate to pull said lever into engagement with said hammer, such means comprising a pivoted key, a switch board, a fixed contact point and a movable contact point on such switch board, means operable between said key and said movable contact point to move said movable contact point into engagement with said fixed contact point when said key is moved, a source of electrical energy, and wired connections from said source of electrical energy to said contact points and from said contact points to said solenoid to complete an electrical circuit through the solenoid when said contact points move together, as described. 85

3. A device of the character described comprising the combination with a rotary type rack carrying type bars and type, of a key for turning said type rack, a lever on said key, means operable between said lever and said type rack for turning said rack a predetermined distance, and means for adjusting this predetermined distance, such means comprising an inclined cam on said lever, an adjustment screw projecting adjacent said inclined cam, a turnable shaft, a finger member on said shaft adapted to engage said cam with the movement of said lever, the amount of such movement being limited by said set screw, such turnable shaft being operatively connected with said type rack whereby, with the movement of said turnable shaft, said type rack will turn, as described. 95

In testimony whereof I affix my signature in presence of two witnesses.

ORIN BENNETT.
